(57) **CLAIM**

The ornamental design for a table board as shown and described.

DESCRIPTION

FIG. 1 is a perspective view of a table board showing our new design;

FIG. 2 is another perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is a perspective view thereof showing the table board in the usage status;

FIG. 10 is a perspective view thereof showing the table board in another usage status;

FIG. 11 is a perspective view thereof showing the table board in another usage status; and,

FIG. 12 is a perspective view thereof showing the table board in another the usage status.

The dashed broken lines illustrate portions of the table board that form no part of the claimed design. The dashed broken lines in FIGS. 9, 10, 11 and 12 are for the purpose of depicting environment and form no part of the claimed design.

1 Claim, 12 Drawing Sheets
